H. F. WAITE,
X-RAY SYSTEM,
APPLICATION FILED JAN. 17, 1920.

1,371,010.

Patented Mar. 8, 1921.

Inventor
HARRY F. WAITE
By his Attorney
O. Avery Edwards

UNITED STATES PATENT OFFICE.

HARRY F. WAITE, OF NEW YORK, N. Y.

X-RAY SYSTEM.

1,371,010.

Specification of Letters Patent. Patented Mar. 8, 1921.

Application filed January 17, 1920. Serial No. 351,988.

To all whom it may concern:

Be it known that I, HARRY F. WAITE, a citizen of the United States, and a resident of the city of New York, county of Queens, 5 and State of New York, (whose post-office address is 252 West 29th street, New York city,) have invented a new and useful Improvement in X-Ray Systems, of which the following is a specification.

10 The object of my invention is to provide a system of this class in which a single step-up transformer may be used for either of two X-ray generating tubes where it is desired to have one exposure following another without shifting the apparatus.

A further object is to avoid arcing and corona effects when the switch is thrown in the high tension circuit.

For a more detailed description of my invention, reference is to be had to the accompanying drawings, forming a part hereof, in which—

Figure 1 is a sectional view of a transformer suitable for my system.

25 Fig. 2 is a diagrammatic view of this system.

Throughout the various views of the drawings, similar reference characters designate similar parts.

30 My improved system 1 is provided with an alternating current generator 2 which is connected to the primary 3 of a transformer 4 by suitable wires 5 and 6, all of which may be in the conventional manner. The transformer 4 may be of the usual form and is provided with an exterior iron case 7 and has its parts immersed in oil 8 and its secondary 9 has two windings, one of coarse wire 10 of a few turns and one of a fine wire 35 11 of many turns, which coils are connected together and are provided with three leads 12, 13 and 14, the leads 12 and 14 being at the extreme ends of the secondary 9, and the lead 13 being common to the coarse and fine 40 winding, as indicated.

The cover 15 of the transformer has a central opening through which extends a shaft 16 which, at its upper end, is provided with a handle 17 and its lower end with a disk 50 18 which extends into the oil 8 and is immersed therein. This cover 15, has a pin 19 which enters a corresponding slot 20 in the disk 18 and limits the throw of this disk so

that it is restricted in its movement to the limits required by the switch, as will be explained below. The wire 12 runs to two contacts 21 and 22 on top of the disk 18; the wire 13 runs to two contacts 23 immediately below the contacts 21 and 22 on top of the disk 18. The wire 14 runs to the contacts 24 and 25. These contacts are so spaced, one with regard to the other, that when the apparatus is in the condition shown in Fig. 2, the contacts 22 and 23 energize the cathode 26 of an X-ray tube 27, and heat this cathode 65 to incandescence through suitable conductors 28 and 29 and the anode 30 of this tube is connected to the contact 25 through a wire 31. The slot 20, pin 19 and the contacts 21 and 24 are so arranged and disposed that 70 when the handle 17 is turned so as to oscillate the shaft 16 to the other limit of its movement, the contacts 21 and 23 will be connected to the hot cathode 32 of an X-ray tube 33, the connection being had 75 through two wires 34 and 35, respectively, and the anode 36 of this tube 33 is connected by a wire 37 to the contact 24.

For convenience the wires 28, 29, 31, 34, 80 35 and 37 are provided with suitable binding posts 38 which are preferably provided with suitable designations so that the transformer 4 may be readily connected to the tubes 27 and 33 in the desired manner.

From the foregoing, it is apparent that 85 in my system there is an oil immersed switch in the secondary circuit of the transformer which has three leads running to this secondary winding, and is so arranged and disposed that either of two hot cathode tubes 90 95 may be connected with this secondary so as to be in an operating condition and that both tubes cannot be made to operate simultaneously. Furthermore, as the contacts of the switch are immersed in oil, no corona or arcing effects are possible.

While I have shown and described one embodiment of my invention, it is obvious that it is not restricted thereto, but is broad enough to cover all structures that come 100 within the scope of the annexed claim.

Having thus described my invention, what I claim is:

In an X-ray system, a source of alternating current, a transformer with its primary 105 connected to said source and a secondary,

two leads running from said secondary, two X-ray generating tubes with two wires from each of the same, and oil immersed means in the transformer for connecting the 5 two leads of the secondary with the corresponding two leads of either, but not both of the X-ray generating tubes at the same

time, which means is so arranged and disposed that either tube may be connected and the other disconnected at the volition of the 10 person operating the apparatus.

In testimony whereof, I have hereunto set my hand this 6th day of January, 1920.

HARRY F. WAITE.
